UNITED STATES PATENT OFFICE.

JOSEPH Y. HUMPHRIES, OF WOODSDALE, NORTH CAROLINA.

PLANT-HILL MARKER.

1,179,315.

Specification of Letters Patent. Patented Apr. 11, 1916.

Application filed September 2, 1914. Serial No. 859,895.

To all whom it may concern:

Be it known that I, JOSEPH Y. HUMPHRIES, citizen of the United States, residing at Woodsdale, in the county of Person and 5 State of North Carolina, have invented certain new and useful Improvements in Plant-Hill Markers; and I do hereby declare the following to be a full, clear, and exact description of the invention, such as will enable others skilled in the art to which it 10 pertains to make and use the same.

This invention relates to land markers, and more especially it is a machine for marking land which has already been formed into 15 parallel ridges into which it is desired to insert the plants. These ridges run across the field at a predetermined distance apart, say three and one-half feet, and one of the objects of the present invention is to mark 20 points in them at about or a little less than the same distance apart, namely three feet, so that the entire field will be checked and can be plowed or cultivated in both directions after it has been planted.

25 Another object of the invention is to so construct the machine that scraper sections are carried in front of the runners which do the marking, these scrapers standing at a decided angle to the runners so that they 30 cut through rather than ride over the crowns of the ridges. The scrapers are of such length that they displace said crowns for a little distance on each side of the path formed by the runners, so that the surplus 35 earth will not be thrown onto the tender plants by the process of subsequent cultivation.

The machine possesses other details and advantages which will appear from the following specification and claim, and which are brought out in connection with the accompanying drawings wherein:

Figure 1 is a plan view and Fig. 2 a side elevation of this machine complete.

45 Referring now by reference numerals to the accompanying drawings, the numerals 1, 1 designate two runners which in a full-sized machine will be about four feet in length and one by six inches in size, and the 50 same may be made of plank such as is available to the average user. To the lower face of the front end of each runner is secured a flat metallic plate or shoe 2 which extends beyond the extremity of the runner and is 55 upturned in an abrupt angle, and its front

end 3 pierced with two holes. Overlying and secured to this shoe is the scraper section 4, also by preference made of wood and beveled along its lower edge as at 5 to lie in the angle of the shoe between its upturned 60 end and the front extremity of the runner. In order that the earth in the crowns of the ridges through which the runner passes, may be pushed aside and not permitted to fall into the path made by the runner, the 65 length of this scraper section is preferably about twice the width of the runner. These 70 runners are connected by a superstructure whose construction is capable of considerable modification but as shown it may be described as follows: Against the rear side of each scraper section and across the upper edge of the same extends the lower leaf of an L-iron cross bar 6, and bolts 7, 7 pass through this leaf, through the scraper section, and through the holes in the upturned 75 front end 3 of the shoe whereby the parts are held together detachably. Said leaf is also provided with additional holes as shown, so that the exact position of the runner with respect to the cross bar can be adjusted as desired. The other runner at the 80 opposite side of the machine is similarly constructed and the parts similarly connected. To each runner is secured a knee 8 of A- 85 shape as shown, and from the apex of the knee a brace 9 extends forward to the cross bar 6, to whose upper leaf it is riveted or bolted as at 10 into one of a number of holes which permit adjustment as above described. 90 The two knees are connected by a rear cross bar 16—also by preference of L-iron—whose lower leaf overlies the braces 9 and is provided with a number of holes 15, and through one of these holes passes a bolt 14 which secures the rear end of the brace to the cross bar and the latter to the knee. The obvious 95 purpose is to enable the lateral adjustment of parts at this point, the same as the structure above described adapts the machine for lateral adjustment at its front end. Secured to the front cross bar 6 at points 17, as by being riveted or bolted to upper leaf of this cross bar as shown, are two handles 18 whose rear ends have grips or hand-holds 19, these 100 handles being connected by a cross rung 20 at a proper point and being braced as at 21, the lower end of the brace by preference being engaged with the same bolt which connects the braces 9 with the rear cross bar 105 110

16, or with another bolt passed through one of the holes 15 if the machine is adjusted for a rather wide travel.

I would make the runners, the scrapers, 5 and the handles of wood, and the remainder of the structure of metal, and a full-sized machine will weigh between fifty and sixty pounds.

The draft is accomplished by hitching a 10 horse or a pair of horses to the front cross bar in any suitable manner not necessary to emphasize.

In connection with this machine I preferably employ a gage for indicating the 15 line along which the nearest runner of this machine should be driven when returning across the field. This consists of a rod 20 pierced with a number of holes 21' corresponding with the series of holes for adjustment as described above, these holes 21' being near the center of the rod. At each 20 end of the latter a finger 22 depends from it, made preferably of metal and of a length to cause its lower end to travel just above the 25 ground, and yet of sufficient resiliency to permit the finger to yield in case it strikes an obstruction. The rear end of the braces 9 are carried past their points of connection with the rear cross bar and are turned into 30 loops 24, preferably provided with upright eyes 25. In these loops the bar or rod 20 is slidably mounted, and when one finger lies against one loop, one of the holes 21' in the bar or rod will be in registration with the 35 eye through the other loop, and a pin 26 may be dropped therethrough to hold the parts in this position. On the return trip across the field, the gage will be shifted to the other side in a manner well understood. 40 This bar or rod may be of wood or metal as desired, and its use is obvious.

It will need no further illustration to make it clear that if desired I might build a machine with more than two runners, but 45 in that case the pair of handles would be disposed in about the center of the width of the machine so that it could be operated by a single man. He travels behind the machine, which is drawn forward by a horse 50 or a team of horses, and the operation and use of this device are as follows: Assuming that the land is to be planted with tobacco, it is first plowed and harrowed and formed into ridges extending across the field three 55 and a half feet apart. With the runners standing three feet apart, center to center, this machine is then driven across the field in a line at right angles to the rows or ridges, and their crowns are knocked off by the 60 scraper sections. Immediately the shoe rides over the part of the ridge remaining, and then the runner flattens it out and supports the superstructure while the machine passes on to the next row or ridge. Attention 65 is directed to the fact that the angle

between the runner and the scraper (which is the same as the angle between the body 2 and the front end 3 of the shoe) is rather abrupt as best seen in Fig. 2, and this construction I employ purposely in preference 70 to curving upward the front end of the runners as usual in sledged machines which are to travel over the ground. The purpose obviously is to permit the angle to knock off or to scrape away the crowns of the ridges, 75 rather than to ride over them. In the action desired, the runner moves straight forward along a substantially level line. If its front end were upturned on a curve, it would often ride over the ridge without cutting through it as I desire, and the runner would be constantly following a sinuous line. Yet if the device as I construct it should strike a stone or stump, the inclination of the front end 2 of the shoe and the body of the 80 scraper 4 is sufficient to permit it to pass over the obstruction without injury to the machine or the horse. Heretofore it has been necessary to knock off the top or crown of the ridge by two strokes of a hoe, and then flatten it out by tamping with the same hoe, and it will be obvious that by the use of a machine of this kind a much larger 85 volume of work can be done than could be accomplished by a single operator with a 90 hoe. Moreover, by the use of the gage attachment the field will be checked, and the 95 plants can be cultivated by plowing both ways subsequently. The purpose of the 100 scraper sections is to knock off so much of the crowns of the ridges adjacent to the 105 points where the plants are to be set, that subsequent cultivation can be done with a horse implement without causing loose earth to fall onto the tender plants, thus doing away with the necessity for cultivating by hand and with care.

Especial attention is directed to the fact that the shoes supplement the scrapers, and the runners follow the shoes and flatten out 110 parts of the ridges but are wide enough not to indent the soil. The result is that the land is best prepared for planting in hills, and is checked both ways as set forth.

Where the parts are connected I prefer to 115 use bolts of standard size which may readily be purchased in the open market, and the use of bolts permits the members to be disconnected as for the substitution of worn or broken parts or for the purpose of storage 120 or transfer.

What is claimed as new is:—

In a hill marker for land which has been formed in parallel ridges, a pair of wide, flat runners standing parallel and rigidly 125 spaced from center to center a distance substantially equal to that between said ridges, a shoe having a flat body underlying the front portion of each runner and its front end turned up at an angle to its body, two 130

scraper sections carried by the upturned ends of the shoes and longer than the width of the runners but with their inner ends spaced from each other, and a superstructure connecting the runners and sections and disposed wholly above them, the whole for use substantially as described.

In testimony whereof I affix my signature in presence of two witnesses.

JOSEPH Y. HUMPHRIES.
